UNITED STATES PATENT OFFICE.

CHARLES P. KIMMEL, OF GARY, INDIANA.

RAIL-JOINT.

1,145,023.

Specification of Letters Patent.

Patented July 6, 1915.

Application filed August 28, 1914. Serial No. 859,065.

To all whom it may concern:

Be it known that I, CHARLES P. KIMMEL, a citizen of the United States, and resident of Gary, in the county of Lake and State of Indiana, have invented certain new and useful Improvements in Rail-Joints, of which the following is a specification.

This invention relates to improvements in joints for railway rails, and it has as its main and primary object the provision of a joint of this character which is constructed and designed to afford a high degree of rigidity, thereby firmly to support the contiguous rail ends and maintain the same in parallel relation. The invention, therefore, obtains the decided advantage of eliminating battering of the ends of the rails incident to the passage of the wheels of the rolling stock thereover, and effectually prevents "dubbing" of the ends of the rails—a feature of objection prevalent in rail joints as commonly employed.

Furthermore, the invention also aims to provide a novel form of rail joint wherein provision is made to overcome wear on the angle bars under the head of the rails at their ends, the construction of the joint being such as to provide a tight, compact relation of the angle bars to the head of the rails, thus obtaining bracing of the rail ends and precluding relative movement of the same. By reason of this alinement of the ends of the rails is maintained and sidewise movement of the rails is also prevented.

A further object contemplated by the present invention is the production of a rail joint of such construction as also to prevent separation of the meeting rail ends in the event of the angle bars becoming loose or entirely detached from the rails. This insures safety and enables the rails to be held in proper alinement until the angle bars can be tightened or replaced by new ones, and obviously reduces liability of accidents to a minimum.

With these general objects in view, and others which will appear as the nature of the improvements is better understood, the invention consists substantially in the novel construction, combination and arrangement of parts hereinafter fully described, illustrated in the accompanying drawings and finally pointed out in the appended claims, but it will be also understood that the form of the invention herein disclosed is only a preferred embodiment thereof and that the

same is therefore susceptible of change, modification and variation and the right is accordingly reserved to change, modify or vary the invention as falls within the spirit 60 thereof.

In the drawings: Figure 1 is a side elevation of a rail joint constructed in accordance with the present invention and illustrated in applied position at the meeting ends of two 65 contiguous rails. Fig. 2 is a transverse sectional view thereof, illustrating the parts in their initial position of application. Fig. 3 is a similar view, the parts being illustrated as fully applied.

Referring in detail to the accompanying drawings, the numeral 10 designates the meeting ends of a pair of railway rails and 11 the base plate of the herein described joint. The plate 11 follows the general contour of railway joint plates, the same being provided with depending ribs 12 at its under side to take into the wooden ties and thus prevent lateral movement of the plate. At the marginal portions of the plate 11 are 80 provided upwardly extending inwardly directed flanges 13. These flanges are designed to overlap the base flanges of the rails 10 and are formed integral with the plate 11, as clearly disclosed in Figs. 2 and 3. It 85 will be noted, however, that each of the flanges 13 at a point adjacent to its joinder with the plate 11 is reduced in thickness in order to provide a bending point and thereby enable the flanges 13 to assume the inwardly directed position illustrated in Figs. 2 and 3. This reduction in thickness is accomplished by the formation of a longitudinally extending groove 14 and by the formation of this groove it will also be noted that 90 an inwardly disposed rib 15 is provided at the inner surface of each of the flanges 13. The purpose of this rib is to take against the upper contiguous surface of the base flanges of the rails in the initial position of 100 the parts as illustrated in Fig. 2 so that the body of the plate 11 will be drawn into close contact with the underside of the rail bases. This will appear more fully hereinafter.

Associated with each of the flanges 13, and arranged in superimposed relation thereto, is an angle or splice bar 16. The upper and lower surfaces of each of these bars 16 are slightly inclined as at 17 and 18 respectively, thereby providing wedging surfaces, 110 and these surfaces coöperate with the inclined under-side of the heads of the rails

and the upper face of the adjacent flange 13 so that each of the angle bars 16 serves in the capacity of a wedge as between the heads of the rails and said flanges.

- 5 Each of the angle bars 16 exerts a compressive strain upon the flange 13 with which it is associated, and to the attaining of this end the bars 16 are perforated at spaced intervals as at 19, said perforations 10 receiving a series of bolts 20 having the usual threaded nuts 21 upon their threaded ends. The bolts 20 pass through enlarged openings 22 formed in the webs of the rails 10, and it will be noted at this point that 15 the size of these openings is slightly greater than the diameter of the bolts 20 in order that the latter may have free movement in said openings when the parts of the joint are being assembled. This also provides for 20 a proper expansion and contraction of the rails under climatic changes.

In assembling the joint of the present invention at the meeting ends of a pair of rails it will be understood that the base 25 plate 11 receives the ends in the manner illustrated in Fig. 2, the flanges 13 being then in their initial position and sufficiently spaced from the base flanges of the rails to enable free movement of the base plate with 30 respect to the ends. The angle bars 16 are then applied to the sides of the webs of the rails and the bolts 20 introduced through the openings 19 and 22. In this position the lower sides of the angle bars rest upon the 35 flanges 13, while their upper sides abut against the inclined lower sides of the rail heads. As the nuts 21 are tightened upon the bolts 20 the angle bars 16 are gradually drawn inwardly and toward the webs of 40 the rails, and in this movement it is obvious that the wedge surfaces 17 in following the inclined undersides of the rail heads will cause a downward movement of the angle bars, while the beveled lower faces 18 there- 45 of will also follow the inclined surfaces of the flanges 13. This movement of the bars 16 compresses the flanges 13 upon the bases of the rails and forces said flanges to the position illustrated in Fig. 3, thus clamp- 50 ing the rails tightly within the base plate 11. In the initial stage of assembling the parts the internal ribs 15 seat against the edges of the base flanges. As the downward pressure is exerted upon the flanges 13 it 55 will be seen that the ribs effectually hold the rail bases upon the plate 11 and in the gradual compression of the flanges this plate is drawn into tight relation with the rails. As indicated the inward movement 60 of the angle bars 16 under stress of the tightening of the bolts, serves effectually to create a wedging action between the heads of the rails and the flanges 13, and by reason of this it will be seen that the bars 16 65 serve to support the rail heads in alinement

and preclude battering of the rails incident to the passage of the rolling stock over the meeting ends. Furthermore, in the event of the loosening of the bars 16 or their entire detachment from the rails, the flanges 70 13 will also prevent the lateral movement of the rail ends and thus reduce the liability of accident to a minimum.

Having thus described the invention, what is claimed as new and desired to be secured 75 by Letters Patent is:

1. In a rail joint, the combination with a base plate provided at its marginal portions with inwardly extending flanges adapted to overlie the base flanges of the rails seated 80 upon said plate, each of said flanges having an inwardly disposed rib for engagement with the base flanges of the rails, of means for compressing the flanges of the base plate upon the base flanges of the rails to 85 hold the latter within the base plate.

2. In a rail joint, the combination with a base plate provided at its marginal portions with inwardly-extending flanges adapted to overlie the base flanges of the rails seated 90 upon said plate, the inner face of each of said flanges adjacent to its point of joinder with the base plate being longitudinally grooved to provide a bending point, whereby to permit movement of the flanges relatively to the base plate, of means for compressing the flanges of the base plate upon the base flanges of the rails to hold the latter within the base plate. 95

3. In a rail joint, the combination with a 100 base plate provided with flanges adapted to overlie the base flanges of the rails seated upon said plate, each of said flanges having a portion reduced in thickness to provide a bending point whereby to permit movement 105 of the flanges relatively to the base plate, of means for compressing the flanges of the base plate upon the base flanges of the rails to hold the latter within the base plate.

4. In a rail joint, the combination with a 110 base plate provided at its marginal portions with inwardly-extending flanges adapted to overlie the base flanges of the rails seated upon said plate, the inner face of each of said flanges adjacent to its point of joinder with the base plate being longitudinally grooved to provide a bending point, whereby to permit movement of the flanges relatively to the base plate, and also having an 115 inwardly disposed rib for engagement with the contiguous base flanges of the rails, of means for compressing the flanges of the base plate upon the base flanges of the rails to hold the latter within the base plate. 120

5. In a rail joint, the combination of a 125 base plate having upwardly extending rail abutting flanges, and rail base engaging flanges joined to said rail abutting flanges by a relatively thin section of metal, whereby said last named flanges may be readily 130

bent to conform to the contour of the rail base, substantially as described.

6. In a rail joint, the combination of a base plate having spike holes at its marginal edges and provided with rail abutting flanges on its upper surface, rail base engaging flanges springing from said rail engaging flanges and joined thereto by a rela-

tively thin section of metal, and a clamp for securing said joint to the web of a rail, substantially as described.
